(57) **CLAIM**

I claim the ornamental design for a pad for a massage chair,
as shown and described.

DESCRIPTION

FIG. 1 is perspective view of a pad for a massage chair,
showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings show portions of the pad
for a massage chair which form no part of the claimed
design.
